UNITED STATES PATENT OFFICE.

LEWIS HENRY SANFORD AND GEORGE HERBERT SANFORD, OF AUGUSTA, MAINE, ASSIGNORS OF ONE-HALF TO WILLIAM B. TAYLOR, OF ST. LOUIS, MISSOURI.

ELECTRICAL INDICATOR.

SPECIFICATION forming part of Letters Patent No. 768,240, dated August 23, 1904.

Application filed November 10, 1903. Serial No. 180,506. (No model.)

To all whom it may concern:

Be it known that we, LEWIS HENRY SANFORD and GEORGE HERBERT SANFORD, citizens of the United States, residing at Augusta, 5 in the county of Kennebec and State of Maine, have invented a new and useful Electrical Indicator, of which the following is a specification.

This invention relates to indicators of that 10 class employed for exhibiting the names of street-corners, railway-stations, and the like, and has for its principal object to construct a novel and efficient automatic mechanism for use in street-cars, railway-cars, depots, theaters, and the like for indicating intersecting 15 streets or announcing the names and time of arrival of trains or for indicating the next act or subject on a program.

The device may further be used for exhibiting 20 the head-lines of newspapers or for the display of bulletins with or without advertisements.

A further object of the invention is to provide 25 an indicator in which a movable strip or sheet is arranged to carry the matter to be exhibited and in which provision is made for automatically reversing the direction of movement of the sheet when all of the advertisements or other matter has been displayed, 30 this being particularly valuable in connection with street-car lines and railway-trains where the exhibiting-strip may bear the names of the street-crossings or stations in regular order and in which the reversal of the movement 35 of the strip will properly display the names as the car or train makes the return trip.

A further object of the invention is to construct 40 an indicator in which provision is made for moving the strip at intervals to any desired extent, the strip itself being so constructed as to determine the extent of travel and to control the operation of the strip-actuating mechanism.

45 A still further object of the invention is to construct an automatic mechanism which may be set into operation by the momentary ener-

gizing of a circuit from an external source and maintained in operation after being started for any desired period of time.

With these and other objects in view, as will hereinafter appear more fully, the invention consists in the novel construction and arrangements of parts hereinafter described, illustrated in the accompanying drawings, and 50 particularly pointed out in the appended claims, it being understood that various changes in the form, proportions, size, and minor details of the structure may be made 55 without departing from the spirit or sacrificing any of the advantages of the invention.

In the accompanying drawings, Figure 1 is a longitudinal sectional elevation of an electrically-actuated indicator constructed in accordance with the invention. Fig. 2 is an 60 elevation looking from the left-hand end of the mechanism, the casing being shown in section. Fig. 3 is a similar view looking from the opposite end of the indicator. Fig. 4 is a detail sectional view, on an enlarged scale, 65 showing the stop-block for arresting the movement of the exhibiting member. Fig. 5 is a sectional perspective view of a portion of the strip-retarding mechanism and circuit-closing devices for shifting the operating 70 mechanism. Fig. 6 is a detail view showing the method of connecting the exhibiting-strip to the rollers.

Similar characters of reference are employed 75 to indicate corresponding parts throughout the several figures of the drawings.

The mechanism forming the subject of the present invention is arranged within a suitable casing 1, provided at the front with a transparent panel 2, through which the announcements on the strip may be displayed. 80 This casing may be placed in any convenient position in a street-car, railway-car, depot, or other public place. Within the casing is arranged a frame 3, having suitable bearings 85 for a pair of shafts 4 and 5, having metallic winding-rollers 6 and 7, on which is wound a strip 8, formed of any suitable material, the rollers serving alternately as receiving-rollers 90

for the strip, and the ends of said strip being connected to the rollers by means of metallic tapes 9. The outer end of each tape is bent to form a hook that engages with a staple 10, sunk in a recess in the face of the roller in order that the strip may wind evenly on the roller, and the opposite end of the tape extends some distance along one face of the display-strip and thence passes through a slit 15 or opening to the opposite side thereof. These metallic tapes form circuit-closers that operate in the manner hereinafter described to reverse the direction of movement of the strip. The frame is further provided with a plurality of guiding-rollers 12, over which the display-strip is led, a pair of the rollers being so arranged as to expose a portion of the strip to the rear of the transparent panel 2.

On one end of the shafts 4 and 5 is a gear 20, to which motion may be imparted in winding up the display-strip. The frame is further provided with bearings for a main driving-shaft 16, having at one end a small pinion 17, intermeshing with a gear 18, that is carried by a stud 19, projecting from one side of a handled shifting lever 20, fulcrumed at its lower end on the shaft 16. The pinion 17 is rotated when the mechanism is in operation, and this movement is transmitted through the gear 18 to one or other of the gears 15, and all of the gears are preferably formed of raw-bide, vulcanized fiber, or like non-conducting materials. The lever 20 is extended out through a slot in the casing and arranged in 35 convenient position to be shifted by the attendant in accordance with the direction in which the display-strip is to be moved.

At that end of the shaft 16 opposite the pinion 17 is arranged a friction-disk 21, and the shaft also carries at this end a toothed locking-disk 22, with which may engage a tooth 23, carried by and insulated from a movable core 24 of a solenoid 25, that is supported by the frame, the windings of the solenoid being connected in a circuit 26, that leads to a point outside the car or railway-train and is connected to a suitable circuit-closer that may be operated by a projection on the road-bed, by contact with a third rail, 40 or otherwise operated in order to close the circuit and energize the solenoid at the desired intervals, as when nearing intersecting streets or stations, or in a theater the circuit-closing device may take the form of a 45 push-button located in the wings. The frame further carries a rock-shaft 27, at one end of which is secured an arm 28, having a pin-and-slot connection with the movable solenoid, and said rock-shaft further carries a circuit-closing arm 29, at the upper end of which is a metallic block 30, insulated from said arm. When the solenoid 25 is energized and the core raised, the tooth 23 leaves the wheel 22 and arm 28 is raised. This moves the arm

29 to the rear and causes the block 30 to enter between a pair of contacts 31 and 32, that form the terminals of a local circuit by which the strip is moved.

The frame is provided with bearings for the support of a shaft 35, on which is secured a worm-wheel 36, intermeshing with a worm 37 on a shaft 38, held in suitable bearings at the lower portion of the casing, and this shaft 38 is connected to or is formed integral with the armature-shaft of a motor 39 of any desired type. At one end of the shaft 35 is secured a friction-disk 41, and the movement of this disk is transmitted to the friction-disk 21 through an intervening friction-disk 43, that is carried by the core 44 of a solenoid 45, connected in series with the motor.

The strip 8, on which the advertising or other material is arranged, is provided at suitable intervals with slits or openings 46, through which may pass a stop-block 47, hung on the outer end of an arm 48, that is secured to rock-shaft 27. The pivot-pin connecting the arm 48 to the stop-block is rigidly secured to the arm 48 and is provided with a diametral slot for the reception of one end of a flat spring 49, the opposite end of which enters a slot in a small pin 49', carried by the shank portion of the block, so that said block will normally be maintained in a central position and when swung to one side or the other by engagement with an opening in the strip will be instantly restored to its central position as soon as the spring is allowed to act. During the movement of the exhibiting-strip the block 47 rests on the surface of the strip until one of the openings 46 comes into alignment therewith, whereupon the block immediately falls through the opening and stops the strip at the proper point, and this stopping movement further serves to positively stop all of the operating mechanism and to break the local operating-circuit.

In order to retard the unwinding movement of the strip and prevent the accumulation of slack, friction-strips 60 are arranged adjacent to each of the strip-supporting rollers, said strips being formed of metal and bearing directly on the paper or other material of which the strip is formed. The friction strips or bars 60 are carried by arms 61, projecting from rock-shafts 62. The shafts 62 are each provided with helical compression-springs 63, that serve to impart the necessary pressure to the friction strips or bars.

To provide for the automatic shifting of the strip-actuating mechanism, the stud 19, which carries the gear 18, is connected to a bar 65, formed of insulating material, the ends of the bar being connected to the movable cores 66 and 67 of solenoids 68 and 69, respectively, and these solenoids are arranged in circuits that are operated or energized by contact of the friction strips or bars with the metallic tapes 9 in order to shift the position of the

gear 18 from one of the gears 15 to the other when the strip has been fully unwound from one of its carrying-rollers.

The electrical circuits which control the operation of the mechanism are of the most simple character and may be traced in connection with a description of the operation of the mechanism.

- When the circuit including the solenoid 25 is closed, as by any ordinary push-button or other circuit-closing mechanism, the tooth 23 is lifted from engagement with the toothed disk 22 and thence raises the stop-block 47 from engagement with one of the openings 46 in the exhibiting-strip. At the same time the arm 29 is moved and the block enters between the two terminals 31 and 32, closing a circuit which may be traced from a battery X to motor 39, solenoid 45, bell Y, contact 31, block 30, contact 32, and thence to battery. This immediately starts the motor into operation, and the solenoid 45 draws the friction-disk 43 into engagement with the two friction-disks 21 and 41, so that the rotations of the motor 25 will be transmitted to the shaft 16, that carries disk 21. This occurs almost instantaneously and the strip starts to move, so that the opening in the strip passes beyond the strip-block 47. The external circuit-closing device 30 may then be released, and as the stop-shoe rests on the surface of the strip it will be impossible for the tooth 23 to descend or for the block 30 to leave its place between the terminals 31 and 32. The shaft 16 in rotating transmits its movement to one or other of the gears 15, and the receiving-roller is turned to wind up a portion of the exhibiting-strip. When a sufficient quantity has been wound, a second opening 46 of the strip will come under the stop-block 47, and the latter will fall. This immediately breaks the local circuit by withdrawing the block 30 from between the terminals 31 and 32, and the tooth 23 is allowed to descend into contact with the toothed disk, 40 immediately stopping the operation of the latter. At the same time the solenoid 45 is deenergized, and friction-disk 43 will not be pressed into engagement with the disks 21 and 41 with sufficient force to transmit rotative movement. The momentum of the strip at the time the stop-block drops into one of the openings 46 slightly tilts the block, moving it from its vertical position, so that when on a subsequent closing of the external circuit the block is raised it will be impossible for the block to reenter the same opening even if the closing of the circuit is only momentary. This is effected by the small straightening-spring, which restores the block to vertical position as soon as it is released from the opening. This operation is continued at intervals until the exhibiting-strip has been fully unwound from one of the rollers. At this time one of the metallic bars 60 will en-

gage the metallic tape 9 at that end of the strip which is exposed, and the circuit will be completed from a battery Z to arm 61, strip 60, metallic tape 9, metallic winding-roller, to one or other of the solenoids 68 or 69, and thence to the battery in order to change the position of the intermediate gear 18, and after the position of the gear is shifted the mechanism will continue to operate, but in the reverse direction. This is particularly valuable for street-car lines, where at the completion of a trip in one direction the strip will have become unwound, and in starting on the return trip the gear will be shifted and the strip rewound in the opposite direction, correctly displaying the names of the intersecting streets or crossings in their proper order.

The lever 20 is of value, inasmuch as it permits the reversal of the direction of movement of the strip at any point along the line should the car be unable from any cause to complete its trip or on cars or trains that travel but a portion of the length of the road.

Having thus described the invention, what is claimed is:

1. In an indicator, an exhibiting-strip having a plurality of perforations, a receiving-roller for the strip, a motor for actuating the roller, a stop-block adapted to enter the successive perforations and stop the movement of the strip, means connected to the stop-block for checking rotative movement of the roller, and means controllable by the movement of the stop-block for cutting off the supply of the motor-actuating medium.

2. In an indicator, an exhibiting-strip, an electric motor for driving the same, an electrically-actuated means for connecting and disconnecting the motor and strip, circuit-breaking devices controllable by the strip, and circuits in which the motor and the connecting means are included.

3. In an indicator, an exhibiting-strip having a plurality of perforations, a receiving-roller for the strip, a motor, a train of gearing for connecting the motor to the winding-roller, one of the gears being normally disconnected, and means for moving the disconnected gear to operative position in the train.

4. In an electrical indicator, an exhibiting-strip, a receiving-roller for the strip, a motor, a train of gearing for connecting the motor to the roller, one of the gears of the train being normally disconnected, a solenoid for moving the disconnected gear, a circuit in which the solenoid is included, and means for opening and closing the circuit.

5. In an electrically-actuated indicator, an exhibiting-strip having a plurality of perforations, a receiving-roller for the strip, a motor, a train of gearing for connecting the motor to the roller, and including a normally disconnected gear, a solenoid arranged in operative relations to said gear, a circuit in which

the solenoid is connected, a circuit-closer, and a stop-block connected to the circuit-closer and adapted to engage in the perforations of the strip.

5 6. In an electrically-actuated indicator, an exhibiting-strip having a plurality of perforations, a receiving-roller for the strip, a motor, a train of gearing for connecting the motor to the roller and including a normally disconnected gear, a solenoid arranged in operative relation to the said gear, a circuit-closer, a stop-block adapted to engage in the perforations of the strip thereby to assist in stopping the movement of the same, and means connecting said stop-block to said circuit-closer.

10 7. In an electrically-actuated indicator, a perforated exhibiting-strip, a receiving-roller therefor, a motor, a normally disconnected gear-train extending from the motor to the roller, a solenoid for connecting the gear-train, a circuit in which the solenoid is connected, a rock-shaft, rock-shaft supports, an arm carried by the rock-shaft and provided with means for establishing the solenoid-circuit, and a stop-block also supported by the rock-shaft and adapted to engage in the perforations.

15 8. In an electrically-actuated indicator, a perforated exhibiting-strip, a receiving-roller therefor, a motor, a normally disconnected gear-train extended between the motor and the roller, a solenoid connecting the gear-train, an electric circuit in which both the motor and the solenoid are connected, a stop-block for engaging in the perforations of the strip, and 30 a circuit-breaker operable on movement of the stop-block.

9. In an electrically-actuated indicator, a perforated exhibiting-strip, a receiving-roller, a motor, means for connecting the motor to the receiving-roller, a stop-block adapted to enter the perforations of the strip, a toothed wheel movable with the roller and means operable on the movement of the stop-block for engaging said toothed wheel and positively 40 arresting the movement of the roller.

10. In an electrically-actuated indicator, a perforated exhibiting-strip, a strip-operating device, a controlling means for the operating device, a tiltable stop-block operatively connected with the controlling device and adapted 45 to enter the perforations, and means for restoring the stop-block to an initial position.

11. In an indicator an exhibiting element having openings, an operating means, a controlling device for the operating means, and a pivotally-mounted stop-block adapted to engage the openings and connected to the controlling means, and a spring for restoring said stop-block to an initial position when released from the openings.

12. In a mechanism of the class described, a movable exhibiting element having a plurality of openings, an operating means, a controlling device for the operating means, and a tiltable stop member connected to the controlling means, and movable by the momentum of the exhibiting element from an initial position.

13. In an indicator, an exhibiting-strip, a pair of rollers operating alternately as receiving members, a metallic tape connecting the ends of the strips to the rollers, an operating member movable into operable relation with either of the rollers, a pair of solenoids connected to the operating mechanism, and friction-bars for engaging the strips and serving by contact with the metallic tapes to close energizing-circuits in which the solenoids are disposed.

14. In indicating mechanism, an exhibiting-strip, a pair of metallic rollers serving alternately as receiving members, staples arranged in recesses formed in the perforations of the roller, metallic tapes connected to the strip and having hooked end portions connected to the staples, friction-bars bearing on the surface of the strip and adapted to engage said metallic tapes to close a circuit, gears on the respective rollers, a revolute pinion, a lever pivoted concentrically with the pinion, a gear carried by the lever and serving to engage with either of the roller-gears, a pair of solenoids, circuits connecting the solenoids to the respective rollers, and a lever extending out through the casing of the indicator to permit the manual shifting of the mechanism.

In testimony that we claim the foregoing as our own we have hereto affixed our signatures in the presence of two witnesses.

LEWIS HENRY SANFORD,
GEORGE HERBERT SANFORD.
